UNITED STATES PATENT OFFICE.

WILLIAM D. COOK, OF HARVARD, NEBRASKA.

ROTARY ENGINE.

SPECIFICATION forming part of Letters Patent No. 261,313, dated July 18, 1882.

Application filed May 2, 1882. (No model.)

To all whom it may concern:

Be it known that I, WILLIAM D. COOK, of Harvard, in the county of Clay and State of Nebraska, have invented a new and useful 5 Improvement in Rotary Engines, of which the following is a full, clear, and exact description.

My invention consists in the novel arrangement of the steam and exhaust ports of rotary engines, and in devices for reversing the movement of the engine, as hereinafter described and claimed.

Reference is to be had to the accompanying drawings, forming a part of this specification, 15 in which similar letters of reference indicate corresponding parts in both the figures.

Figure 1 is a sectional elevation of my improved rotary engine in a plane transversely of the shaft. Fig. 2 is a transverse section 20 at right angles to Fig. 1.

A is the cylinder, closed at its ends by heads a a, and containing the piston B, which is made as a solid cylinder, and fixed upon the shaft b, that passes through the heads a. 25 The piston B is of smaller diameter than the interior of the cylinder A, so that an annular steam-way or space is left around the piston, and upon the piston, at one side, is an abutment, d, projecting against the inner surface 30 of the case. The piston is also formed at its mid-length with an annular flange, e, which, taking against the inner surface of the case, divides the steam-way into two separate compartments, and I place two abutments, d, diametrically opposed, upon the piston B, one abutment being at one side of the dividing-flange, e, and the other at the other side, the object being to obtain a continuous and more uniform pressure of the steam than could be 35 obtained if only one abutment were used in a single steam-way. At its upper side the cylinder A is formed with a steam-chamber, C, to which steam is to be supplied by pipe f, and within this chamber is fixed a block, g, 40 of semicircular form, so as to form two separate ports or passages, h h, from the steam-pipe f to the interior of the cylinder.

At i i are the exhaust-pipes, connected midway between the steam-ports h h.

50 In the steam-chamber, above the block g, is a plate, l, which is in form the segment of a hollow cylinder, and is sustained between cross-bars or rollers m m, so that it may be

moved endwise. On the ends of the plate l gates n n are pivoted, and a cross-shaft, o, 55 fitted in the block g, is provided with a pinion, p, which meshes with a rack on the under side of the plate l, so that by turning the shaft o the plate l is moved endwise, and either gate n brought down upon the piston 60 B in an operative position, the other gate at the same time being withdrawn within the port h.

At q is a valve or gate, jointed to plate l for movement therewith, to direct the steam from 65 the pipe f to either port h, according to the direction in which the piston is to be revolved.

In operation the steam passes through the port h at one side, and, entering the steamway, presses upon the abutment d, and the gate n 70 at that side being lowered cuts off the steam from the exhaust-port, so that there is a continuous pressure upon the abutment until it makes nearly a complete revolution and reaches the exhaust-ports or pipe i. After 75 passing the exhaust-pipe the abutment will raise the gate n, and, passing in front of the steam-port h, will again receive the steam-pressure. To reverse the engine, it is only necessary to move the plate l, so that the gate n, 80 that has been down, shall be raised, and the other gate moved downward, and then to turn the valve q, so that the steam may pass through the other port h and enter the steamway.

Having thus described my invention, I claim 85 as new and desire to secure by Letters Patent—

1. In a rotary engine, the combination, with the steam-chamber C, provided with the pipe f and the ports h, of the slide, having a rack on its under face, and provided with the pivoted gates n q and the pinion p, substantially 90 as and for the purpose set forth.

2. In rotary engines, the turning-valve q and the sliding plate l, carrying the gates n, in combination with the steam-chamber C and ports h, and the steam-supply pipe f, substantially as described, for operation as set forth. 95

3. In rotary engines, the combination of the shaft o, pinion p, and curved plate l, provided with a rack engaging the pinion and 100 carrying the pivoted gates n at its outer end, substantially as described.

WILLIAM D. COOK.
